[**] Term: 14 Years

[21] Appl. No.: 718,257

Primary Examiner—Horace B. Fay, Jr.

Attorney, Agent, or Firm—Wenderoth, Lind & Ponack

[22] Filed: Jun. 20, 1991

CLAIM

[30] Foreign Application Priority Data

The ornamental design for an automotive telephone control unit, as shown and described.

Mar. 4, 1991 [JP] Japan 3-5565
[52] U.S. Cl. D14/138; 379/454;
D12/192; D14/247
[58] Field of Search D14/138, 247; 379/454;
D12/155, 192

DESCRIPTION

[56] References Cited

FIG. 1 is a right side, top and front perspective view of an automotive telephone control unit showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a sectional view taken along line A—A in FIG. 2;

FIG. 9 is a sectional view taken along line B—B in FIG. 2; and,

FIG. 10 is a perspective view of the control unit showing it installed in a dashboard of a vehicle.

The broken line showing of environmental structure surrounding the full line automotive telephone control unit is for illustrative purposes only and forms no part of the claimed design.
